[57] CLAIM

The ornamental design for a dual mode spreader, as shown and described.

DESCRIPTION

FIG. 1 is a perspective view of a dual mode spreader in a broadcast mode embodying my new design, the perspective looking down on the front and right side thereof; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a view similar to FIG. 2 showing the dual mode spreader in a folded storage or transporting position; and, FIG. 9 is a view similar to FIG. 1 with the dual mode spreader in a drop mode.
